GOBLET

Raymond T. Kimble, Cambridge, Ohio, assignor to The Cambridge Glass Company, Cambridge, Ohio, a corporation of Ohio

Application April 4, 1956, Serial No. 40,922

Term of patent 14 years

(Cl. D36—8)

I claim:

The ornamental design for a goblet, substantially as shown.
